UNITED STATES PATENT OFFICE

101,378

DESIGN FOR A BASE FOR DISPLAYING STATUETTES OR OTHER ORNAMENTAL ARTICLES

Thomas Mayerhofer, Chicago, Ill., assignor to
F. H. Noble & Co., Chicago, Ill., a corporation of Illinois

Application August 12, 1936, Serial No. 64,378

Term of patent 7 years

To all whom it may concern:

Be it known that I, Thomas Mayerhofer, a citizen of the German Republic, residing at Chicago, in the county of Cook, State of Illinois, have invented a new, original, and ornamental Design for Bases for Displaying Statuettes or Other Ornamental Articles, of which the following is a specification, reference being had to the accompanying drawing, forming a part thereof.

view of a base for displaying statuettes and other ornamental articles embodying my new design.

Figs. 2 and 3 are, respectively, a side elevational view and a plan view of the same; and

Fig. 4 is a perspective view of said base.

I claim:

The ornamental design for a base for displaying statuettes or other ornamental articles, as shown.

THOMAS MAYERHOFER.
